US0D1042702S

(12) United States Design Patent (10) Patent No.: US D1,042,702 S
(45) Date of Patent: * Sep. 17, 2024

(54) PUNCHING BAG

(71) Applicant: Kun Jiang, Jiangxi (CN)

(72) Inventor: Kun Jiang, Jiangxi (CN)

() Term: 15 Years

(21) Appl. No.: 29/933,400

(22) Filed: Mar. 19, 2024

(51) LOC (14) Cl. 21-02

(52) U.S. Cl.

USPC D21/787

(58) Field of Classification Search

USPC D21/439, 440, 662, 680, 688, 698, 722, D21/787, 798

CPC A63B 69/20; A63B 69/203; A63B 69/205; A63B 69/206; A63B 69/24; A63B 69/26; A63B 69/32; A63B 69/34; A63B 2244/102; A63B 2244/106; A63B 2244/10; A63B 2244/104; A63B 69/224; A63B 69/22; A63B 2220/53; A63B 2071/026

(57) CLAIM

The ornamental design for a punching bag, as shown and described.

DESCRIPTION

FIG. 1 is a perspective view of the punching bag showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the figures illustrate portions that form no part of the claimed design.

1 Claim, 8 Drawing Sheets
